UNITED STATES PATENT OFFICE.

ELLIICK H. GOLLINGS, OF CHICAGO, ILLINOIS.

ROTARY PUMP.

1,263,550.

Specification of Letters Patent. Patented Apr. 23, 1918.

Application filed October 29, 1914. Serial No. 869,190.

To all whom it may concern:

Be it known that I, ELLICK H. GOLLINGS, a citizen of the United States, residing in Chicago, in the county of Cook and State 5 of Illinois, have invented a new and useful Improvement in Rotary Pumps, of which the following is a specification:

My invention relates in general to rotary pumps and has for its object broadly the 10 provision of a rotary pump for water and other liquids consisting of a minimum number of moving parts so arranged that a continuous and substantially even flow from the pump may be produced.

15 A principal object of this invention is the provision of an effective and durable pump in which all valves and equivalent constructions will be entirely eliminated. These parts soon wear and are difficult to maintain 20 in adjusted relation and their elimination is therefore extremely desirable.

A further object of the invention is to provide such a device in which sliding contact between moving parts will be reduced 25 to a minimum thereby eliminating as far as possible wear of the parts in service.

A still further object of the invention is the provision of a device of this character which may be cheaply constructed, readily 30 assembled and installed and which may be operated with a minimum expenditure of power.

On the drawings:

Figure 1 is a longitudinal vertical sectional view of a pump embodying my invention with the parts arranged in one position;

Fig. 2 is a partial horizontal, sectional view of the same;

40 Fig. 3 is a view similar to Fig. 1 showing the parts separated;

Figs. 4, 5 and 6 are transverse vertical sectional views taken respectively on the lines 4—4, 5—5 and 6—6 of Fig. 1 and

45 Figs. 7, 8, 9 and 10 are diagrammatic views showing a complete cycle of operation.

The pump embodying my invention and shown on the drawings comprises a suitable 50 base 11 having at each end an elongated bearing 12, 13 disposed at a substantial distance above the base upon supports or legs 14. The central axis of the bearing 13 is

disposed above or out of alinement with the central axis of the bearing 12 and in the 55 present instance this is accomplished by providing the boss 15 upon the end of the base 11 beneath the bearing 13, although it will be manifest as the invention is better understood that the central axes of the bearings 12, 13 may be otherwise arranged it only being necessary for the purposes of this invention that the said axes be out of alinement each with the other and in parallelism therewith.

65 Two hollow shafts are provided, one through each bearing. One of these shafts, that indicated on the drawings at 16, constitutes a feed shaft and the other, that indicated at 17, a delivery shaft. Each of 70 these shafts carries a rotating member, that of the shaft 16 being indicated generally at 18 and that of the shaft 17 being indicated generally at 19 in Fig. 3. These rotating elements coöperate to lift or pull the water 75 or other liquid being pumped into the device through the hollow shaft 16 and then force it out through the hollow shaft 17. Each member is threaded upon the end of its respective shaft so that the shaft as well 80 as the member rotates as will be hereinafter described.

85 The rotatable member 18 which is fastened upon the end of the shaft 16 consists of a hub 21 in which is engaged an end of the shaft 16 and from which extends a circular imperforate web 22 from the outer edge of which extends a deep cylindrical flange 23. A second outwardly extending deep cylindrical flange 24 is provided within the flange 23 upon the web 22, this flange however having an opening 25 at one side 90 extending from the web to its outer face. The space within the flange 24 is divided into two substantially equal compartments 95 by a partition 28 extending from the central point of the opening 25 to the diametrically opposite point. The ends of this partition are straight and extend throughout the depth of the flange 24. The center of the 100 partition is formed of a continuation of the hub and is curved in the present instance oppositely in its outer and inner halves. This is provided by cutting away the hub at opposite sides at 27 and 29 throughout half 105 the cylindrical wall, a cross web 26 being

formed integrally with the curved parts 31 thus provided to separate the compartments. It will be noted on viewing the figures that this arrangement permits free communication between one compartment and the inlet shaft 16 and between the other compartment and the outlet or delivery shaft 17. The end 32 of the partition, which is the end adjacent the opening 25, is connected through the 10 opening to the outer flange 23 by a partition 33 having tongues 34 among its opposite longitudinal edges adapted to fit into appropriate grooves in the end 32 of the partition 28 and in the adjacent face of the flange 23. 15 The space within the flange 24 is thus divided into two compartments each communicating with the space between the flanges 23 and 24. For the sake of convenience we will indicate the compartments by the letters 20 *a* and *b* the compartment *a* being the compartment which communicates with the shaft 16 through the opening 27 and the compartment *b* being the compartment which communicates with the outlet shaft 17 25 through opening 29. A web 35 forms a partial closure for the outer edge of the flange 24 and this web closes completely the compartment *a* at one side and is provided with a central aperture 36 to permit communication 30 with the shaft 17 and compartment *b*.

The rotatable element 19 secured upon the shaft 17 consists of a hub 37 having an outwardly extending web 38 formed integral therewith upon the edge of which is a cylindrical flange 39 cut away at 41. The flange 39 is of appropriate diameter to permit it to be inserted between the flanges 23, 24 of the rotatable member 18, the edges left in cutting away the portion 41 alining with the 40 edges of the flange 24 provided in forming the opening 25 already described. The diameter and thickness of the cylindrical flange 39 are preferably such that when the parts are assembled as will be later described 45 the inner surface of the flange 39 may contact with the outer surface of the flange 24 at one side of the device and the outer surface of the flange 39 may contact with the inner surface of the flange 23 at the other 50 side. In the present instance the first mentioned contact is provided at the top of the device and the last mentioned at the bottom, the position of these contacts being determined by the relative position of the axes 55 of the rotatable elements.

Viewing Figs. 3 and 6 it will be noted that the web 38 is cut away back of and beneath the cut away portion 41 of the flange 39 as indicated at 42. The cut away portion is 60 shaped to receive a pair of disk members 45 slidably engaging the partition 33 extending between the flange 23 and the partition 28 within the flange 24. The members 45 have a flat surface in sliding engagement 65 with the sides of the partition 33 and have

arcuately curved faces engaging in the recess 42.

The parts are assembled by merely inserting the rotatable member 19 within the rotatable member 18 the length of the flanges 75 23, 24 and 39 being appropriate to permit the web 35 to engage the web 38 with the inner edge of the flange 39 engaging the face of the web 22. The flange 23 extends beyond the outer face of the web 35 when in this position and is thickened at 46 to receive a plurality of fastening bolts 47 extending through a closing plate 48 having an aperture 49 at its center through which the hub of the member 19 extends. The aperture 49 80 is of appropriate form and size to permit relative movement of the shafts 16 and 17 and their attached members to rotate about the respective axes. Rotation is imparted to the pump through a sprocket wheel 50 secured upon the hub 21 of the member 18 and this rotation is transmitted to the member 19 the turning of the one member necessarily requiring the turning of the other although if desired separate means may be provided 85 for turning each rotatable member and its corresponding shaft. A packing or gasket member is secured upon the hub 37 of the rotatable member 19 and comprises in the present instance a disk 51 carrying a packing 52 at its face adjacent the web of the rotatable member for bearing against the outer face of the closing plate 48 the central portion of this plate being rendered smooth for the purpose. 90

Water is delivered to the shaft 16 and removed from the shaft 17 through bushings 53 connected to collars 54 which in turn are threaded to the ends of the bearings 13 and 12 said collars forming a part 105 of stuffing boxes 55 for the prevention of leakage.

The operation of the pump will now be described reference being had more particularly to Figs. 7, 8, 9 and 10 it being remembered that the compartments labeled *a* in these figures are connected with the inlet and the compartments labeled *b* with the outlet of the pump. The theory of operation of the pump embodying my invention 110 and just described requires the provision of two main compartments continuously and alternately increasing and diminishing in size the increasing compartment serving continuously to draw in water or other 115 liquid and the decreasing compartment to expel it through the outlet. For the purpose of brevity and clearness the operation will be described with the pump full of water it being understood that the theory of 120 operation is the same when the pump starts to run and when it only contains air or a mixture of air and water.

Viewing Fig. 7 in which the partition 33 extends downwardly and which may be con- 125 130

sidered the initial arrangement in the cycle, it will be noted that two compartments *c* and *d* are formed between the flanges 39 and 24 separated by the partition 33. The compartment *d* is in communication with the compartment *b* and the compartment *c* with the compartment *a*. As the parts are rotating in the direction of the arrow it is obvious that the compartment *d* will 10 decrease in size and the compartment *c* increase correspondingly. The water contained in the compartment *d* will be forced as the rotation continues into compartment *b* and then to the outlet. At the same time 15 the space in the compartment *c* will increase and water will be sucked from the compartment *a* into the compartment *c*, new water or liquid being drawn into the compartment *a*. At this time, as soon as the parts leave 20 the position shown in Fig. 7, two new compartments are formed, namely, *e* and *f*, the compartment *e* opening up in communication with compartment *c*, must be filled by liquid from either the compartment *a* or the 25 compartment *c*. The compartment *f* immediately begins to diminish and water from it as well as from the compartment *d* must be forced through the compartment *b* to the outlet. Water is thus being drawn into two 30 compartments in this stage of the operation and being forced from two to the outlet. In effect the compartments *e* and *c*, which are increasing, constitute a single chamber of constantly enlarging capacity, the enlargement of its capacity drawing water from the inlet, and in effect the compartments *d* and *f*, which are the compartments decreasing in size, constitute a single chamber constantly diminishing and forcing water out through the supply or outlet. At 35 the end of the next quarter revolution, when the parts have arrived at the position shown in Fig. 9, it will be noted that the opening in the flange 39 and the opening in the flange 24 are brought together, eliminating entirely the compartment *d* and reducing by half the compartment *f*. At this stage the compartment *c* has increased to its maximum 40 and is closed off full of water. In this figure 45 this compartment is lettered *g* for the sake of clearness. The compartment *e* has enlarged until it is equal in size to the compartment *f*. In passing to the next quarter revolution or that shown in Fig. 10, the compartment *c* opens and begins to draw 50 water from the compartment *a*, the compartment *e* enlarging as shown. As soon as the parts move from the position shown in Fig. 9 the compartment *g* is drawn into 55 communication with the chamber *b* and becomes the compartment *d* already described. From this point on this compartment diminishes in capacity; the compartment *f* also diminishing until the parts reach the 60 position shown in Fig. 7, when the compartment *f* passes out of existence and the compartment *e* reaches its maximum or that lettered *h* in Fig. 7.

It will be noted from the drawings that the space *g* between the flanges 24 and 39 and the space *h* between the flanges 39 and 23 are both crescent shape. The provision of the two crescent shape spaces arranged and divided as described, provide a continuous and almost even radial opening opposite the openings into the compartments *a* and *b*, for as this opening is cut down from one compartment it is enlarged correspondingly from the other so that water may be drawn into the compartment *b* and out of the compartment *a* in a substantially constant amount, one decreasing compartment cooperating with the other decreasing compartment and one increasing compartment cooperating with the other increasing compartment. This gives a substantially even flow of water from the pump. The difference in the rate of diminution or increase of one compartment or the compartment in a portion of one of the crescents being compensated for by the diminution or increase of the other diminishing or increasing compartment.

No valves are necessary and there is substantially no sliding of the parts one on the other, the flange 39 rolling in contact with the flanges 23 and 24. There is of course a slight sliding movement between the partition 33 and the half circular disks 45, but this is of relatively small importance and should any wear occur new disks 45 can readily be provided.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a rotary pump the combination of two rotatable members in rolling contact constructed and arranged to form between them at different times in their cycle of rotation pumping chambers of which two are of continuously changing capacity, one of said chambers being connected with an inlet and the other with an outlet, and each of said chambers subdivided into two parts each having a variable rate of change of capacity, the sum of the rates of change in said chambers being substantially a constant quantity.

2. In a rotary pump the combination of a plurality of rotary members constructed and arranged to form pumping chambers at different times in their cycle of operation, two

1. of said chambers being disposed one within the other and being alternately filled with liquid to be pumped and subsequently connected to the outlet of the pump, and while so connected both said chambers decreasing in capacity at different and compensating rates.
3. In a rotary pump the combination of a plurality of rotary members constructed and arranged to form pumping chambers at different times in their cycle of operation, two of said chambers being disposed one within the other and being always in communication with the inlet and increasing in capacity while so connected at different and compensating rates.
4. In a rotary pump the combination of a plurality of rotary members constructed and arranged to form pumping chambers at different times in their cycle of operation, a pair of chambers being connected with the inlet and a pair with the outlet, those with the inlet increasing in capacity and those with the outlet decreasing in capacity, the members of each pair being located one within the other and increasing and diminishing respectively at different and compensating rates.
5. In a rotary pump the combination of a plurality of rotary members constructed and arranged to form pumping chambers at different times in their cycle of operation, a pair of chambers being connected with the inlet and a pair with the outlet, those with the inlet increasing in capacity and those with the outlet decreasing in capacity, the members of each pair being located one within the other and increasing and diminishing respectively at different and compensating rates, said chambers automatically reversing their connection after passing their zero point.
6. In a rotary pump the combination of rotatable members in rolling contact and constructed and arranged to form between them at different times in their cycle of rotation a pair of crescent shaped pumping chambers, oppositely arranged and separated by a common wall, said chambers being in communication with each other at a shifting point, a partition dividing said communication between the inlet and the outlet of said pump and a portion of said crescent on one side being in communication with the outlet and the portions on the other side with the inlet.
7. In a rotary pump the combination of rotatable members in rolling contact and constructed and arranged to form between them at different times in their cycle of rotation a pair of crescent shaped pumping chambers, the ends of one crescent being arranged at the center of the other, a partition movable around the axis of one of said members and extending across said chambers and adapted to move from the center of one chamber around to the center of the other, one side of said partition being in communication with the inlet and the other side with the outlet of said pump, said partition thereby first forcing water from one-half of one crescent to the outlet and replacing this displacement by water from the inlet of the other side of said partition.
8. In a rotary pump the combination of a rotatable element having a pair of outwardly extending flanges providing communicating compartments, a second rotatable member having an outwardly extending flange adapted to be positioned between the flanges of the first mentioned member, said last mentioned member being mounted to rotate about an axis offset from the axis of said first mentioned member and dividing one of said compartments into two crescents and a partition for dividing said crescents.
9. In a rotary pump the combination of a rotatable element having a pair of outwardly extending flanges providing communicating compartments, a second rotatable member having an outwardly extending flange adapted to be positioned between the flanges of the first mentioned member, said last mentioned member being mounted to rotate about an axis offset from the axis of said first mentioned member and dividing one of said compartments into two crescents and a partition in said first mentioned member for dividing said crescents and forcing water out of them to the pump outlet and drawing water into them from the pump inlet.
10. In a rotary pump the combination of two rotatable members having their axes of rotation disposed out of alignment, said members being movable together at like velocity, overlapping flanges between said members forming compartments for drawing water into one compartment and forcing it out from the other.
11. In a rotary pump the combination of two rotatable shafts arranged end for end with their axes disposed out of alignment, flanged members on the adjacent ends of said shafts, one of said flanged members extending into the other and forming compartments therewith adapted to draw water into said pump and to force water out from said pump, and means for rotating said shafts with their members.
12. In a rotary pump the combination of a pair of rotatable hollow shafts arranged end for end with their axes out of alignment and provided with members in rolling contact and at their adjacent ends, such members providing compartments for drawing water into one of said shafts and forcing it out through the other, and means for rotating said shafts in unison.
13. In a rotary pump the combination of a pair of rotatable shafts arranged end for

end with their axes disposed out of alignment, flanged members on the adjacent ends of said shafts arranged with the flanges overlapping and forming compartments, ⁵ means for inclosing one of said members and its flange within the other member to form closed compartments of varying capacity connected with the inlet and outlet of said pump, and means for rotating said shafts in unison.
